UNITED STATES PATENT OFFICE.

CHARLES RALEIGH AND WILLIAM V. D. KELLEY, OF BROOKLYN, NEW YORK, ASSIGNEES,
BY MESNE ASSIGNMENTS, TO PRIZMA INCORPORATED, A CORPORATION OF MAINE.

METHOD OF PRODUCING COLORED PHOTOGRAPHIC IMAGES.

1,333,730.

Specification of Letters Patent. Patented Mar. 16, 1920.

Application filed April 3, 1914. Serial No. 829,166.

To all whom it may concern:

Be it known that we, CHARLES RALEIGH and WILLIAM V. D. KELLEY, citizens of the United States, residing at Brooklyn, in the 5 county of Kings and State of New York, have invented certain new and useful Improvements in Methods for Producing Colored Photographic Images, of which the following is a full, clear, and exact specification.

10 This invention relates to motion pictures, and has particular reference to means and a method of obtaining reproductions of pictures in natural colors in a much more 15 natural manner than has heretofore been attained. By this invention, it is possible to produce pictures in natural colors with reduced speed per second, which gives a reduced length of film for exhibiting a given 20 subject. By this invention, color fringing is also very largely if not entirely eliminated.

In one method of producing motion pictures in colors, it has been proposed to either 25 take or exhibit three pictures in succession through color screens, each of which passes one of three primary colors, three successive pictures each recording values corresponding to one only of said three colors. With 30 this method, owing to the widely different color values it is necessary to project all three of these single color images in the space of time usually used to project a single black and white image, that is, at the rate 35 of forty-eight or more pictures per second. This method is disclosed in United States patent to Lee, *et al.*, No. 645,477.

In a later method, it has been sought to reduce the speed to about thirty pictures 40 per second by taking or projecting pictures through screens recording two color values instead of three, which color screens have been so selected as to only somewhat approximate natural colors when projected, 45 violet being almost absent. This method is disclosed in United States patent to Smith No. 941,960.

In both of the above methods, of which the latter is at present in use, each section 50 of the color screen is of an independent color, and each image of the film has only a record of one color value.

According to this invention, we reduce the speed to twenty-four pictures per second or thereabout, by causing each film 55 section to record values corresponding to two of three primary colors, which color values are derived from a composite screen, so arranged as to pass at least two of the three primary colors for each image. Starting 60 with red, blue and green as the primary or predetermined colors, in one form we divide a movable screen into sections, each of which passes two of these colors. Thus one section will pass red and blue and record corresponding color values on the first picture of the film, the next section of the screen will pass green and red and record corresponding color values on the film, and the next section of the screen will pass blue 65 and green and record corresponding color values on the film. This is for taking, and in projecting it will be understood that positives made from these negatives and each having two color values will be projected 70 through a similar screen. We may accomplish this result either by making each section of the screen of a composite color, or by dividing each section of the screen into two predetermined colors and moving it faster 75 so as to expose both colors of each screen section during one picture exposure. By our method, it will be seen that a series of color screens or filters operating on or in conjunction with three photographic images, 80 causes the cycle of colors to be completed twice in the space of three photographic images. For comparison, the aforementioned three primary color process completes the color cycle once in three images, 85 and in the incomplete two color process once in two images, while with our process the complete color cycle is actually completed in an average of one and one-half images. Color fringing is reduced by this invention, 90 because each two-color image embodies a color common to the succeeding image. At the same time, eye fatigue will be reduced, because two of the three nerve color centers will at all times be excited, since all 95 images will contain in some degree mixtures of colors, so that the successive images blend one into the other. The photographic exposure in taking is also increased, giving 100

better pictures, because of exposing each section of film to two colors and a longer length of time instead of one as heretofore.

Our invention is graphically illustrated in 5 the accompanying drawings, wherein—

Figure 1 represents a section of a taking camera;

Fig. 2 represents a section of film associated with the three section composite color 10 screen;

Fig. 3 represents a different color screen, containing the three primary colors and which will be revolved to expose two colors for each film exposure, and

15 Fig. 4, a still different color screen.

1 represents a box containing reels 2, 2 having film 3 wound thereon which is exposed through aperture 4 and the usual lens and shutter mechanism 5. 6 represents a 20 shaft carrying the screen 7, which is revolved in synchronism with the driven shaft 8. The screen 7 shown in Fig. 2 is provided with three sections P, OY and GB, which correspond to the colors approximately 25 purple, orange yellow and green-blue. That is, each of these screen sections is a composite made up of two of the three primary colors red, blue, green, and thereby each section will pass two of these three 30 colors. With this form, the screen will be revolved so as to expose one section with each section S of the film. The purple screen in Fig. 2 passes and records red, and the yellow screen passes and records red, 35 with the result that red is recorded in taking and obtained in projecting. The same applies to all the other colors, it being a matter of mixing the correct amounts of two filter colors in order to get a resultant 40 third color. The correct amount of purple and yellow mixed gives as result, red, because the blue in the purple will cancel the yellow. If we mix yellow and blue-green in proper proportion, we obtain green, because 45 the blue will cancel the yellow. If we mix blue green and purple in proper proportion, the green with a little blue will cancel the red and we obtain pure blue. Thus we obtain primary reds, greens and 50 blues by this process of cancellation in both taking and projecting. In Fig. 3, the screen is composed of three colors R, B, G, corresponding to the primary or predetermined colors red, blue and green. The sections R 55 and B of the screen will show while section S of the film is exposed, the sections G and R will show while the section S¹ is exposed, and the sections B and G will show while the section S² is exposed. In this 60 manner, each film section will record values corresponding to two colors, it being understood that a film having a panchromatic emulsion will be employed for the negatives. That is, a film which is rendered sensitive 65 to all colors, and is well known in the art.

A projection of positives with the screen shown in Fig. 3 is accomplished in a similar manner, that is each image area will be shown through two of the screen sections, one screen section being common to each 70 two succeeding images, the screen making two complete revolutions for each three images, and being of course started in the right relation to the color values recorded by the respective images.

75 The apparatus of Fig. 1 represents the manner in which the negatives are taken, from which negatives positives are made and used in any suitable projecting apparatus, except that a color screen is added containing sections of color corresponding to the taking screens and properly synchronized therewith. Thus each picture will be projected through a screen passing two colors, one of which colors appears on two adjoining images, so that as before stated the color cycle is completed in the space of one and one-half images, or twice in three images. It will be seen that by the method of this invention, wherein two color 90 values are combined in each image, the mean intensity of the light for each image is substantially constant. That is, the total light does not materially vary in successive images, so that they all receive practically the 95 same degree of exposure. This result is due to the fact that each exposure is made with two light waves, that for one color being of relatively short, and that for the other color, being of relatively long wave length. When 100 combined in each image, the mean or resultant wave lengths (which determine the intensity of the image) do not substantially vary to such an extent as to require different treatment in developing, printing or 105 projecting for individual images. This is not only advantageous in obtaining the images, but is equally advantageous in developing the negatives, making the positives, and projecting them.

110 The invention can also be carried out in connection with a two color composite screen, as shown in Fig. 4. In this form, one sector GB is composed of green and blue, and the other sector OR of orange-red. 115 The screen is revolved so that two-thirds of the total composite color area shows for each image. This gives all of the red, and part of the green on image S, then equal exposures of the next image S' to red and 120 green, and on the third image S² of the series, all the green and part of the red. During each exposure, approximately 240° of colors are shown by the screen on each. The first cycle gives 180° of red, and 60° of 125 green, the second cycle 120° of both red and green, and the third cycle 180° of green and 60° of red. These two composite colors will correspond, when properly shown, to first, purple, second, yellow, and third, green- 130

blue. That is, the three successive images S , S' , S'' will have color values corresponding generally to these three composite colors. The screen shown in Fig. 4, is preferably used for projecting. The screen filters are such that practically all of the spectrum is covered viz:—blue-green for one half, orange-red for the other half. Three conditions exist: (1) At one period there are equal areas of red and green-blue on one image giving a yellow condition, then (2) a large section of red and a small section of green-blue the red therefore predominating, giving the purple condition, then (3) a large section of green-blue and a small section of red, the green predominating giving the blue-green condition. This is nevertheless a three color screen in result, as will be seen upon consideration. A properly exposed film taken with our process, having good color value, will give satisfactory results when projected, even though the colors of the projecting screen only approximate the colors of the taking screen. That is, we may project through any of the screens, shown in Figs. 2, 3 or 4. The great value of using the screen shown in Fig. 4 in projecting is due to the difficulty of using a blue-violet color. It is difficult, in practice, to get sufficient light through this B-V section to bring its intensity up to the intensity of the red and green sections of a three section showing screen. On the other hand it is quite simple to get the same intensity of light through a shutter composed of red in one section and green-blue in the other. Spinning such a screen, as we have described herein actually gives three color conditions.

This form is especially advantageous with electric arc light taking or projections, which contains a preponderance of violet or blue, because the excess of blue can be readily compensated for to produce the same balance as exists in natural light. Thus if 180° of the screen is orange-red, and the other 180° blue-green, and the screen be revolved at proper speed, image S will receive 180° of red and 60° of blue-green, image S' will receive 120° each of red and blue-green, and image S'' will receive 180° of blue-green and 60° of red. In each cycle of three pictures, therefore, there will be a correction for the excess blue in the projecting arc light. Thus the connection can be made either in taking, or in projecting as may be

more convenient. The same principle also applies in taking by arc light.

It will be understood that by a composite screen, we refer either to a screen as shown in Fig. 2 containing the three composite colors, or the screens shown in Fig. 3 in which the three primary colors are employed, or that shown in Fig. 4, having two composite colors, but the screen to be so operated as to expose two of the colors to each image, and the same color appearing on two successive images.

It will be seen that the screen is composite to each image even though its individual sections are composed of single colors, the composite effect being obtained by revolving the sections of the screen asynchronously with respect to each image.

Where we use the term film in this specification, it will be understood that we refer to any transparent support for sensitized photographic emulsion, and intend thereby to include flexible or stiff plates, or continuous rolls of any known character.

It will be further understood that the invention is not restricted to the employment of a single width film with successive images, as our method of simultaneously obtaining records of two colors on each image and of projecting them to reproduce the natural colors is applicable to various other forms of film.

Where we speak of composite colors as purple, we mean a color that will pass practically only the red and blue when viewed in the spectroscope; of yellow, a color that passes red and green; of blue, a color passing blue, violet and green.

Having thus described our invention, we declare that what we claim as new and desire to secure by Letters Patent, is:—

In motion picture recording, the method which consist in recording on successive panchromatic image areas red-blue, blue-green, and green-red color values through a screen composed of red, blue and green sections constituting white light, whereby each area records white light minus a constituent.

In testimony whereof we affix our signatures, in presence of two witnesses.
